UNITED STATES PATENT OFFICE.

PAUL MAUSER, OF OBERNDORF-ON-THE-NECKAR, GERMANY.

FIRING MECHANISM FOR RECOIL-LOADING PISTOLS WITH FIXED BARRELS.

1,041,648.

Specification of Letters Patent.

Patented Oct. 15, 1912.

Application filed October 18, 1910. Serial No. 587,729.

To all whom it may concern:
Be it known that I, PAUL MAUSER, privy
commercial councillor, a subject of the King
of Wurttemberg, residing at Oberndorf, in
the Kingdom of Wurttemberg, Germany,
have invented certain new and useful Im-
provements in Firing Mechanism for Recoil-
Loading Pistols with Fixed Barrels, of
which the following is a full, clear, and ex-
10 act description.

This invention relates to an improvement
in or modification of the invention de-
scribed in the specification accompanying
my application for Patent No. 532,198 of
15 December 9, 1909.

In the trigger mechanism described in
said specification the sear consists of a two
armed bell crank lever pivoted at its center
and furnished at one end with an upwardly
20 projecting rigid arm, which forms the sear
proper, while at the other end it acts in
conjunction with an upwardly directed de-
tent lever for holding and releasing the
sear, which at its lower end is pivoted to
25 the trigger, while its upper end engages
with the sear lever. Now this invention re-
lates to a further addition to or improve-
ment of this mechanism by means of which
it is rendered impossible that the pistol
30 should be fired or the trigger actuated when
the breech is not completely closed, that is
to say, when the breech block is not in the
proper position.

The accompanying drawings illustrate
35 the new construction, wherein—

Figure 1 shows the weapon with the
breech in the proper position after firing,
and Fig. 2 shows the weapon with the
40 breech block in the partially open position
and with the sear lever locked against being
actuated.

The arrangement of the trigger me-
chanism is in its main features the same as in
the above mentioned specification. The sear
45 has the form of a two armed lever $a^1 a^2$
which is provided at its rear end with an
upwardly directed projection a^3 , which
forms the sear proper, while its front end
acts in conjunction with the detent lever c
50 pivoted to the trigger z .

The present improvement embodies a
structure wherein the lever arm a^1 of the
sear is provided with an upwardly extend-
ing projection a^0 which, when the breech
55 has been operated in the proper manner,
engages with a corresponding recess v^0 of

the breech block v . By this means it is
insured that the pulling of the trigger can
only be effected when the parts are in the
position shown in Fig. 1, that is to say, when
the breech block is moved as far as possible
forward, or in other words, when the breech
has been effectually closed. Should it hap-
pen that the breech block is not in this po-
sition, that is to say, should the recess v^0
not be situated exactly over the projection a^0
of the sear lever arm a^1 , the projection will
stand opposite the full portion of the side
 v^1 of the breech block with the result that,
notwithstanding the pressure on the trig-
ger, the sear lever $a^1 a^2$, cannot rotate to the
extent requisite for its sear to release the
firing pin and is consequently locked.

What I claim as my invention and desire
to secure by Letters Patent is:

1. A trigger mechanism for a recoil load-
ing pistol, comprising a sear ($a^1 a^2$), in the
form of a two armed lever and having a
rigid arm (a^3) which forms the sear proper,
an upward projection (a^0) upon its fore-
end, a trigger engaging said sear, means for
disengaging said trigger and sear upon pull-
ing of the trigger, and a breech block (v)
having a recess (v^0) therein into which said
projection (a^0) is adapted to project, where-
by the pulling of the trigger can be effected
only when the breech bolt is in its closing
position.

2. A firing mechanism for recoil operated
fire arms, comprising a trigger, a sear, a
firing-pin, a recoil operated breech-bolt, and
cooperating means on said sear and on said
breech-bolt for preventing operation of said
sear to release the firing-pin except when
said breech-bolt is in position to close the
breech, said sear being released by said trig-
ger upon the trigger being pulled, whereby
said cooperating means may be disengaged
to permit recoil of the breech-bolt.

3. A firing mechanism for recoil operated
fire arms, comprising a trigger, a sear, a
firing-pin, a recoil operated breech-bolt,
having a recess therein, and a projection
upon said sear adapted to enter said recess
in the breech-bolt only when the breech is
in closed position, said sear being released
by said trigger upon the trigger being
pulled, whereby said projection may be dis-
engaged from said recess in the breech-bolt
to permit recoil of said breech-bolt.

4. A firing mechanism for recoil operated
firearms, comprising a trigger, a sear in the

- form of a two arm lever, a firing-pin adapted to be engaged by one arm of said sear, a recoil operated breech-bolt, having a recess therein, and a projection upon the other arm of said sear adapted to enter said recess in the breech-bolt when the breech is in closed position to prevent release of said firing-pin except when said breech-bolt is in position to close the breech, said sear 5 being released by said trigger upon said trigger being pulled, whereby said projection may be disengaged from said recess in the breech-bolt to permit recoil of the breech-bolt.
- 10 15 5. A firing mechanism for recoil-operated fire-arms, comprising a trigger, a sear, a

catch-device upon said trigger adapted to engage said sear, means for disengaging said catch device from said sear, a firing pin, a recoil-operated breech-bolt, and co-operating means on said sear and on said breech-bolt for preventing operation of said sear to release the firing pin except when said breech-bolt is in position to close the breech.
